UNITED STATES PATENT OFFICE

2,415,511

VENTILATED IGNITION DISTRIBUTOR FOR
INTERNAL-COMBUSTION ENGINES

Marion Mallory, Detroit, Mich.

Application May 7, 1945, Serial No. 592,470

8 Claims. (Cl. 123—103)

1

This invention relates to a ventilated ignition distributor for an internal combustion engine.

During the operation of an ignition distributor for an internal combustion engine ozone is generated by the high tension spark or arc which is set up by the circuit breaker and the distributor arm and points. Ozone is undesirable in a distributor housing because it corrodes the metal.

It is an object of this invention to produce a simple arrangement for ventilating the distributor housing. This object is accomplished by utilizing the suction actuated device for an engine governor as a bellows to sweep the ozone out of, and draw fresh air into, the distributor housing.

Fig. 1 is a view partly in section showing my combined governor and ventilated ignition distributor housing.

Fig. 2 is a section along the line 2—2 of Fig. 1.

Fig. 3 is a section along the line 3—3 of Fig. 2.

Fig. 4 is a section along the line 4—4 of Fig. 1.

For purposes of illustration, I have shown an engine governor which is actuated by intake passageway suction of the type shown in my copending application Serial No. 466,961, filed November 25, 1942. Therefore, I will only briefly describe this governor.

The parts of my governor are as follows: governor housing 1, intake passageway 2, outlet 3 to the engine intake manifold, throttle valve 4, tension spring 5 tending at all times to open throttle valve 4, suction device comprising a sealed housing 6, flexible diaphragm 7, suction chamber 8, atmosphere chamber 9, passageways 10, 11 and 12 connecting suction chamber 8 with orifices 13 and 14 in the intake passageway 2, conduit 15 connecting passageways 10, 11 and 12 with axial passageway 16 in ignition distributor shaft 17 which is run off the engine in a conventional manner (not shown), centrifugally unbalanced valve 18 in valve housing 19, air bleed orifice 20, bypass groove 21 in valve 19, tension spring 22 which tends to hold centrifugal valve 18 open, distributor housing 23, cap 24 for distributor housing 23, air inlet 25, air cleaner 26. The distributor is a conventional ignition distributor having the usual circuit breaker, distributor arm and points. A seal or gasket is provided between cap 24 and housing 23 so as to make the joint therebetween air-tight and shaft 17 is also provided with an air-tight fit in housing 23 so that all the air entering housing 23 must enter through air cleaner 26 and inlet 25. The inside of cap 24, of course, communicates with the inside of housing 23.

2

For evacuating the air and ozone from inside the distributor housing (23, 24), I connect the inside of the housing by means of conduit 27 and conduit 28 into chamber 9 of suction device 8. Chamber 9 communicates with atmosphere only through passageway 28, conduit 27, housing 23, inlet 25 and cleaner 26.

The operation of my governor is the same as described in my above specified copending application wherein the intake passageway suction, as modified by air bleeding through orifice 20, passageways 16, 15 and 10, acts upon diaphragm 7 in opposition to tension spring 5 to control throttle valve 4 in accordance with the charge required by the engine to maintain its governed speed. In the operation of my governor, centrifugal valve 18 rides the vacuum and restricts orifice 20 more as the speed of the engine tends to fall below its governed speed than when the engine is running at its governed speed.

When the engine is first started and speeds up from idle to its governed speed, then upon reaching its governed speed valve 18 will momentarily close. Thus, during the operation of my governor, diaphragm 7 will move sometimes toward the right, Figs. 1 and 2, and then again will flex toward the left. In other words, flexible diaphragm 7, under the influence of spring 5 and intake passageway suction, acts as a pump sometimes increasing chamber 9 and sometimes decreasing chamber 9. As diaphragm 7 moves toward the right, Figs. 1 and 2, air is forced through conduit 27 and into distributor housing 23 and thence out through passageway 25 and air cleaner 26. At times some of the air displaced by rightward movement of diaphragm 7 will pass through air bleed orifice 21 and conduit 15 into the intake passageway, but usually diaphragm 7 will be moving toward the right when valve 18 is closed or nearly closed so that most of the air displaced in housing 23 will pass outwardly through opening 25. As diaphragm 7 moves toward the left, enlarging chamber 9, this diaphragm action will draw fresh air through air cleaner 27 and inlet 25 into distributor housing 23. Thus, the pumping action of diaphragm 7 will effectively clean the ozone and any other harmful gases out of housing 23.

I claim:

1. In an internal combustion engine having an intake passageway, an ignition distributor including a housing having an inlet therein, a suction responsive device including a movable member actuated by changes of pressure in the intake passageway, a communication between

said suction responsive device on one side of said movable member and said intake passageway whereby said movable member is actuated by intake passageway suction, a conduit connecting said suction responsive device on the other side of said movable member into the distributor housing whereby as the movable member of the suction device is actuated by changes of pressure in the intake passageway gas is forced out of the distributor housing and air drawn in through said inlet.

2. In an internal combustion engine having an intake passageway, a throttle valve controlling fluid flow through said passageway, an ignition distributor including a housing having an inlet therein, a suction responsive device including a movable member actuated by changes of pressure in the intake passageway on the engine side of said throttle valve, a communication between said suction responsive device on one side of said movable member and said intake passageway whereby said movable member is actuated by intake passageway suction, a conduit connecting said suction responsive device on the other side of said movable member into the distributor housing whereby as the movable member of the suction device is actuated by changes of pressure in the intake passageway gas is forced out of the distributor housing and air drawn in through said inlet.

3. In an internal combustion engine having an intake passageway, a throttle valve controlling fluid flow through said passageway, an ignition distributor including a housing having an inlet therein, a suction actuated pump having a fluid pumping chamber and actuated by changes of pressure in the intake passageway on the engine side of said throttle valve, a conduit connecting the fluid pumping chamber of said pump into the distributor housing whereby as the pump is actuated by changes of pressure in the intake passageway gas is alternately forced out of the distributor housing and air drawn in through the housing inlet.

4. The combination as set forth in claim 3 wherein said pump comprises a pump housing and a flexible diaphragm having a connection with said throttle valve, the said flexible diaphragm dividing the pump housing into a suction chamber connected into the intake passageway on the engine side of the throttle valve, and a pumping chamber connected by the first-mentioned conduit with the distributor housing.

5. In an internal combustion engine having an intake passageway, a throttle valve controlling fluid flow through said passageway, a suction responsive device actuated by changes of pressure in the intake passageway on the engine side of said throttle valve, a connection between said suction responsive device and the throttle valve, said suction device having a suction chamber connected into the intake passageway on the engine

side of the throttle valve and a pumping chamber, a distributor housing, an air bleed orifice located within said distributor housing, a conduit connecting said air bleed orifice with the suction chamber of said suction device, a centrifugal valve controlled in accordance with the speed of the engine and arranged to close as the engine reaches its governed speed whereby said suction device responds to the intake passageway pressure to move said throttle valve toward closed position, a conduit connecting the distributor housing with the pumping chamber of said suction device whereby as the suction device responds to changes in intake passageway pressures to actuate said throttle valve a pumping action is set up which alternately forces gas out of the distributor housing and draws fresh air into the housing.

6. The combination as set forth in claim 5 wherein the centrifugal air bleed valve mechanism comprises a distributor shaft, a valve housing mounted on the distributor shaft and having an air bleed orifice therein and a centrifugally unbalanced valve mounted in the housing offset from the axis of rotation so that the valve itself constitutes the centrifugal weight.

7. The combination as set forth in claim 5 wherein the sole communication between atmosphere and said pumping chamber is through the said conduit and distributor housing.

8. In an internal combustion engine having an intake passageway, a throttle valve controlling fluid flow through said passageway, an ignition distributor including a housing having an inlet therein, a suction actuated pump having a fluid pumping chamber in communication with said ignition distributor housing and a suction chamber in communication with the intake passageway on the engine side of said throttle valve whereby said pump responds to the intake passageway suction, fluid bleed means controlled in accordance with the speed of the engine for bleeding fluid into said suction chamber when the engine is running below a given speed to raise the pressure in said chamber and for closing off said fluid bleed when the engine is operating above said speed to thereby lower the pressure in said suction chamber whereby the pump is actuated as the pressure in the suction chamber changes and air is alternately forced in and out of the distributor housing through the housing inlet.
